UNITED STATES PATENT OFFICE.

BERT A. STOCKING, OF DES MOINES, IOWA.

WASHING MACHINE GEAR.

Application filed February 21, 1927. Serial No. 169,875.

This invention relates to improvements in washing machines and particularly to that type disclosed in my copending application for United States Letters Patent on 5 washing machine, filed July 20, 1925, Serial Number 44,805. This improvement pertains to the manner in which the dolly is mounted on the dolly shaft and the manner in which it is operatively connected with the gear 10 mechanism for imparting motion to said dolly.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a vertical sectional view of the 20 bottom of the washing machine tub taken through the center of the dolly.

Figure 2 is a detail sectional view taken on the line 2--2 of Figure 1.

Figure 3 is a detail sectional view taken 25 on the line 3--3 of Figure 1.

The numeral 10 indicates the bottom end of the washing machine tub, preferably provided with an inclined bottom 11. The central portion of the bottom 11 is provided with a recess 12 in which the dolly disk 13 is mounted. The central portion of the recess 12 is provided with a second recess 14. Secured in the bottom 11 is a post 15, locked in position by means of a nut 16, 30 said post being provided with a collar 17 to assist in supporting the post 15 in an upright position. Said post 15 extends upwardly through the recesses 12 and 14 and has a rack guide 18 pivotally supported on 35 its lower end.

Rotatively mounted on the post 15 is a sleeve 19, the lower end of which is provided with a pinion gear 20. The sleeve 19 is rectangular in cross section and has a 45 round opening extending through its longitudinal center for receiving the post 15. The upper end of the post 15 is provided with an annular groove 21 for receiving a set screw 22 carried by the sleeve 19, said 50 set screw being provided for the purpose of preventing the sleeve 19 from being lifted upwardly and at the same time permitting the sleeve to rotate freely about the post 15.

The dolly disk 13 is provided with an upwardly extending hub 23 having a square opening in its center for receiving the upper

end of the sleeve 19, the dolly being provided with radially extending blades 24 for agitating the water, the blades connecting with the disk 13 and the hub 23 in the manner clearly illustrated. The hub 23 is provided with a pair of oppositely arranged lugs 25 located near the disk 13. Each of the lugs 25 is provided with an opening 26 for receiving a spring actuated retaining pin 27. The inner ends of the pins 27 are designed to rest in a groove 28 formed in the outer surface of the sleeve 19. The inner ends of the pins 27 are rounded so that if a considerable upward pressure is applied to the dolly, the dolly may be lifted from the sleeve 19. The pins 27 are forced outwardly as the dolly is elevated. Each of the pins 27 is provided with a flange 29 for limiting the inward movement of the pins, the pins being yieldably supported in the opening 26 by a spring 30, the tension of which may be adjusted by means of a nut 31. The sleeve 19 is rotated through the pinion 20 by means of a rack 32, which is supported in a suitable groove 33 in the bottom of the tub, and is connected at its free end with a crank 34 driven from the shaft 35.

Thus it will be seen that by providing the set screw 22 and the spring actuated pins 27, I have provided means whereby the dolly will be prevented from being lifted from the sleeve, and the sleeve prevented from being moved upwardly to cause the pinion 20 to disengage the rack 32, as the dolly is being operated, and at the same time permit the dolly to be easily and quickly removed from the sleeve 19 for the purpose of cleaning the recesses 12 and 14, when desired. It is seldom desirable to remove the sleeve 19, and for that reason the set screw 22 is used in place of a spring pin as used in the dolly.

I claim as my invention:

1. In a washing machine, a tub having a bottom member, a post secured in the said bottom member and projected upwardly into said tub, the upper end of said post being provided with an annular groove, a sleeve rotatively mounted on said post, said sleeve being provided with a set screw for entering said groove to prevent longitudinal movement of the sleeve relative to the post, the outer surface of said sleeve being provided with a horizontal groove, a dolly having a hub provided with an opening for receiving said sleeve, the hub of said dolly being provided with a recess, a spring actuated pin

within said recess, the inner end of said pin being rounded and designed to enter the groove of said sleeve, and means for imparting oscillatory reciprocating motion to said sleeve.

2. In a device of the class described, a support, an upright post having an annular groove near its upper end, a sleeve rotatively mounted on the upper end of said post, means carried by said sleeve for entering said annular groove to prevent longitudinal movement of said sleeve relative to said post, said sleeve being rectangular in cross section and having its side faces provided with grooves in alinement with each other, a dolly disk having a hub portion provided with a rectangular opening for receiving said sleeve, the hub of said dolly disk being provided with a recess in alinement with the groove of said sleeve and in communication therewith, a pin slidably mounted in said recess having its inner end rounded and designed to enter the groove of said sleeve, said pin being provided with a rib for limiting its inward movement, a spring for yieldably moving said pin inwardly, an adjust-

ing nut for supporting the outer end of said spring, and means for imparting oscillatory movement to said sleeve.

3. In a washing machine, a tub having a bottom member, an upright post in said bottom, a sleeve rotatively mounted on said post, means for locking said sleeve against longitudinal movement relative to said post, a dolly carried by said sleeve, yieldable means for retaining said dolly in position on said sleeve, means for locking the sleeve against rotary movement relative to said dolly, and means for imparting oscillatory movement to said sleeve. 40

4. In a washing machine, a tub having a bottom, an upright post, a sleeve rotatively mounted on said post, a dolly detachably supported on said sleeve, yieldable means for retaining said dolly against removal 45 from said sleeve, means for operatively connecting said sleeve with said dolly, and means for imparting oscillatory movement to said sleeve.

Des Moines, Iowa, February 14, 1927.

BERT A. STOCKING.
